UNITED STATES PATENT OFFICE.

OTTO RITTER VON EBERHARD, OF BREDENEY, GERMANY, ASSIGNOR TO FRIED. KRUPP AKTIENGESELLSCHAFT, OF ESSEN-ON-THE-RUHR, GERMANY.

SIGHTING DEVICE FOR PROJECTILE-EJECTORS OF AIRSHIPS.

1,159,556.

Specification of Letters Patent.

Patented Nov. 9, 1915.

Application filed January 20, 1914. Serial No. 813,294.

To all whom it may concern:

Be it known that I, OTTO RITTER VON EBERHARD, residing at Bredeney, Germany, a subject of the Emperor of Germany, have 5 invented a certain new and useful Improvement in Sighting Devices for Projectile-Ejectors of Airships, of which the following is a specification.

The present invention relates to a sighting device for projectile ejectors used on air vehicles, especially on flying machines, which device permits, in a new and simple manner, compensation of the deviation of the ejected projectile caused by the wind.

10 In the accompanying drawings, one embodiment of the invention is illustrated: and Figure 1 shows an elevation partly in section of the sighting device; Fig. 2, a top plan view of Fig. 1; Fig. 3 a section along the line 3—3 of Fig. 1, seen from above; and Fig. 4, a section along line 4—4 of Fig. 1, also seen from above. The following figures are in larger scale, and Fig. 5 illustrates a development of the cylindrical surface of 15 one of the details; Fig. 6, a part of Fig. 1; Fig. 7 a section along line 7—7 of Fig. 6, seen from the left; Fig. 8, a section along line 8—8 of Fig. 6, seen from above; and Fig. 9 is a diagrammatic plan view of the 20 sighting device and individual points of the terrain beneath the air vehicle.

In the figures, A denotes a bracket of the sighting device, which bracket is rigidly connected with the stand of the air vehicle.

25 A trunnion a^1 , which extends in vertical position when the air vehicle is in its horizontal equilibrium, is provided on the bracket, and a hood B is mounted to oscillate on this trunnion. Between the hood B and the 30 trunnion a^1 is inserted a self-locking worm gear, the worm C of which carries a small hand wheel c^1 , see Fig. 3, and is mounted to rotate in the hood B and meshes with teeth a^2 of the trunnion a^1 .

35 At one end of the worm shaft protruding through the hood B is fastened a drum C^2 , on the cylindrical surface of which are scribed two curve diagrams, each comprising a great number of curves c^3 and c^4 respectively. Said surface 40 is shown developed in Fig. 5. The purpose and the arrangement of the two curved diagrams will be more fully described below. The drum C^2 is embraced at both of its end faces by two arms b^1 and b^2 mounted on the worm shaft and rigidly connected with each

other by a rib b^3 . A screw spindle D, provided with a small hand wheel d^1 , is mounted to rotate in the arms b^1 and b^2 and relative to which the worm shaft can turn freely. By means of this screw spindle a 45 slide E may be displaced in axial direction along the rib b^3 . On the slide E is provided an index e^1 for the curves c^3 and c^4 . For the purpose of reading the adjustment to be given in axial direction to the index, e^1 , 50 which adjustment corresponds to the speed of the air vehicle, determined, for instance, in well known manner, by means of a stop watch, is provided a division d^2 on the small hand wheel d^1 together with a corresponding mark b^4 on the arm b^2 ranging from 0 to 40 meter-seconds.

55 Mounted to swing loosely on the hood B is provided a fork having two prongs F F^1 by means of a trunnion f^2 , the axis of which intersects the axis of the trunnion a^1 at right angles. A spindle G having a small hand wheel g^1 is mounted in the prongs F F^1 at right angles to the trunnion f^2 , and on this spindle a sleeve H is freely revoluble 60 between the prongs F F^1 . The sleeve H has a circular cut h^1 , see Fig. 1, the axis of its curvature being parallel to the axis of the spindle G. In this cut is guided a sight bar J, which is correspondingly curved 65 along a portion of its length. The curved portion of the sight bar is provided with teeth i^1 meshing with a pinion g^2 , see Figs. 1 and 4, which is rigidly secured on the spindle G. By means of a bar h^2 a pendulum weight H^3 is suspended from the sleeve H, the bar being rigidly connected therewith so that the sleeve H at each adjustment, which the sight bar J is given by 70 means of the gears g^2 i^1 relative to the sleeve, will be retained in a position in which the axis of the bar h^2 remains perpendicular, during the oscillation of the air ship. At the upper end of the sight bar J is situated a semicircular direction plate i^2 75 which is rigidly connected therewith and the plane of the axis of curvature of this plate is parallel with the curved portion of the sight bar. A slide K is adjustable along the circumference of the direction plate i^2 80 upon which slide an arm M is mounted to revolve by means of a radially directed trunnion m^1 , which arm terminates at its free end in a guide sleeve m^2 , see particularly Figs. 6, 7 and 8. In this sleeve m^2 is 85

90 95 100 105 110

carried a square bolt N, the central longitudinal axis of which runs through the intersecting point of the trunnion m^1 and the axis of curvature of the semicircular direction plate i^2 . At the end thereof nearest the axis of curvature of the direction plate i^2 , the bolt N is provided with a notch n^1 situated along its central longitudinal axis. The position of the sight line is determined by means of this notch, in coöperation with a front sight cone i^3 provided at the lower end of the sight bar J situated in the axis of curvature of the direction plate i^2 .

A screw P, see Fig. 8, seated on a small hand wheel P^1 , which is revolubly but not displaceably mounted on the sleeve m^2 , is provided for displacing in the axial direction the bolt N with the notch n^1 , and this screw P is in mesh with internal threads provided in the axial boring of the bolt N. On the circumference of the small hand wheel P^1 is arranged a scale p^2 corresponding to the strength of the wind, which scale extends in both directions from the zero point p^3 , see Figs. 2 and 7, and is provided with similar numbers. The position of the zero point p^3 has been so selected that it registers with the reading mark m^4 , provided for the scale p^2 on the sleeve m^2 , see Fig. 2, when the notch n^1 is situated in the axis of curvature of the direction plate i^2 . The direction which the sight line possesses with the above described adjustment of the notch, will, for the sake of shortness, in the following be called the "main direction" of the sight line. For determining the side direction of the bolt N, carrying the notch n^1 , serves a reading mark k^2 situated on the slide K and an angular division i^4 arranged at the outer edge of the direction scale i^2 , which angular scale comprises angles from 0° to 180° being uniformly numbered with numerals from 0 to 16. The position of the zero point has been so selected that it registers with the mark k^2 , when the central longitudinal axis of the bolt W intersects at right angles with the axis of curvature of the portion of the sight bar J which is curved to the arch of a circle. On this portion of the sight bar is lastly provided an angular scale i^5 which is intended for determining the angle of ejection, this means that angle which the "main direction" of the sight line must form with the axis of the sight bar h^2 , in order that the projectile, supposed to be immune to the action of the wind, may hit a certain point in the terrain, which projectile has been ejected at the moment the "main direction" of the sight line crosses said point of terrain. For reading the scale i^5 a mark h^4 is provided on the sleeve H.

In the diagrammatic plan view, Fig. 9, it has been supposed that the sight bar J has been correspondingly adjusted by means of the gears g^2 so that the sight line is in-

clined as seen from below and in front, and that the direction plate i^2 has a correspondingly inclined position. The point o denotes the projection of the axis of the trunnion a^1 , the point q, the projection of the front sight point determined by the cone i^3 , and the point r the projection of the rear sight point determined by the notch n^1 , when the notch n^1 is adjusted in the axis of curvature of the direction plate i^2 as for instance has been shown in Figs. 2 and 8.

When the air vehicle moves, influenced by a side wind, the direction of travel must obviously deviate a certain angle from the direction of the longitudinal axis of the air vehicle toward the side of the wind direction. If the line $o-a$ denotes the actual speed falling in the direction of the longitudinal axis of the air vehicle, and the line $a-b$ the wind speed w , the line $o-b$ will consequently represent the speed of travel which will be denoted by the character v . Furthermore in the triangle $o-a-b$ the angle $b-o-a$ is equal to the angle δ denoting the deviation in the direction of travel from the longitudinal axis of the air vehicle. Supposing now that the sighting device, by means of turning the small hand wheel c^1 so as to revolve the hood B around the trunnion a^1 , has been swung sidewise from its middle position represented in Fig. 2, so far that the projection $q-r$ of the "main direction" of the sight line falls in the direction of travel, so must the angle in which the hood B has been turned be equal to δ and therefore the turning angle of the drum C^2 proportional to δ . It will be evident from the triangle $o-a-b$ that the value w of the wind speed, under the supposition, that the actual speed $o-a$ were constant, is only a function of the values v and δ , so that if the angle δ and the value v are given, the value w is also determined; the angle δ being determined by the adjustment of the sighting device into the direction of travel, and the value v determined, in well known manner, by a stop watch, for instance. The same also applies to the angle β which the wind speed forms with the direction of travel. Supposing that the angle β is to be measured by that angle through which the side $a-b$ of the triangle has to be turned around the vertex b in clockwise direction in order to bring it in the direction of the side $o-b$ of the triangle, it will follow that the angle β will be measured by the angle $o-b-a$ of the triangle in case that the direction of travel deviates to the left from the direction of the longitudinal axis of the vehicle, as has been supposed in Fig. 9, and in the opposite case will be measured by the supplemental angle.

In the development of the cylindrical surface of the drum C^2 , as represented in Fig. 5, it has been supposed that the drum is bisected along a surface line situated dia-

metrically opposite a longitudinal surface line c^5 to which the mark e^1 points in the middle position of the sighting device as represented in Fig. 2. Let it now be supposed that the traveling speed v is scribed from a certain zero-point in the direction of the surface line C^5 , in a suitably selected scale, which naturally must correspond to the division d^2 , serving to determine the axial adjustment of the mark e^1 ; and let it furthermore be supposed that the angle δ is scribed in such a scale on a line c^6 running circumferentially through the zero-point of the surface line c^5 , that by a turning of the drum C^2 the revolving angle of the hood B, measured from the middle position, will always be the same as the angle produced by the distance of the mark e^1 from the surface line c^5 , measured circumferentially. If now in the coördinate system formed by the line c^5 and c^6 , the ratio between the value w , v and δ is graphically represented by curves, so that each curve represents a constant value of the wind velocity w and coördinates for each curve point represent corresponding values v and δ will be obtained which denote wind velocities of 10, 20, 30 and 40 meter-seconds as represented in Fig. 5. If in similar manner the ratio between the values β , v and δ are laid out, curves c^3 will be obtained. For angles β which only range between 0° and 180° , is then selected the same unit on which is based the division i^4 of the direction plate i^2 , so that the angle $\beta=0$ expresses the scale number 0, and the angle $\beta=180^\circ$ the scale number 16. The curves c^3 , in Fig. 5, all denote the values β for all the whole numbers ranging from 0 to 16.

The operation of the described sighting device is as follows: The sighting device is, if necessary, first adjusted so that the notch n^1 is situated in its zero position, see Figs. 2 and 8, represented by the point r in Fig. 9. The sight line is thereupon directed against the target z , Fig. 9, by turning the small hand wheels g^1 and c^1 , and retained in the direction of the target by continued turning of the small hand wheels g^1 and c^1 . The air vehicle is similarly steered in such a direction that the direction of travel runs through the target. If this is the case, the sight direction of the sighting device need no further change by turning the small hand wheel c^1 , because the vehicle now moves in such a manner that the straight line $o-r-q$ continually coincides with the straight line $o-z$. The drum C^2 is now adjusted by turning the small hand wheel c^1 to correspond to the angle δ . In further advancement in the course it is not necessary to retain the target in the sight line. By the use, for instance, of a stop watch, the traveling speed v is now determined, and the sight bar J adjusted to the ejecting angle corre-

sponding to the obtained traveling speed and the flight altitude, through displacement of the sleeve H by means of the small hand wheel g^1 , until the mark h^4 registers with the division line of the division i^5 corresponding to the ejecting angle. Furthermore the obtained value of v is set on the division d^2 under coöperation of the mark b^4 by turning the small hand wheel d^1 . 70

The mark e^1 receives through this adjustment the axial displacement relative to the drum C^2 , which corresponds to the traveling speed v . The value of angle β which the wind direction forms with the traveling direction will, now be shown through the position which the mark e^1 takes with regard to the curve c^4 ; and the value w of the wind speed will be shown through the position of the mark e^1 relative to the curve c^3 . 75 80

By now turning the small hand wheel p^1 , 85 the bolt N carrying the notch n^1 will be displaced in the axial direction until the mark m^4 , see Fig. 2, registers with the division line of the division p^2 which corresponds to the value w read off the drum C^2 ; and this displacement takes place, according to whether the direction of travel deviates to left or right from the longitudinal axis of the vessel, either toward the outer edge of the direction plate i^2 or in the opposite direction. 90 95 The slide K will furthermore be so adjusted that the mark k^2 registers with that division of the division line i^4 which represents the value of β read off on the drum C^2 . In consequence of this adjustment the projection 100 of the axis of the bolt N would be parallel with the wind direction if the plane of the direction plate i^2 were horizontal and the bolt axis were parallel to this plane. In consequence of the inclination which the direction plate i^2 has obtained through the adjustment of the ejecting angle this will, however, not actually occur. As, however, the inclination of the direction plate is usually 105 comparatively small, it can, as a rule, be 110 supposed that the projection of the axis of the bolt N is with sufficient exactitude parallel to the wind direction.

The hereabove outlined manner of measuring the angle has the advantage over 115 measuring of the prior art that the division i^4 can be used both for deviations of the traveling direction to right and left of the longitudinal axis of the vessel. Lastly the arm M has to be turned so far around the 120 axis of the trunnion m^1 until the mark m^3 representing the altitude of the vessel registers with the division line of the division k^1 . The projection of the rear sighting point determined by the notch n^1 after making the 125 above mentioned adjustments as denoted by s, Fig. 9. In the revolution of the arm M around the axis of the trunnion m^1 it always relates to comparatively small angles of revolution. This has therefore very little in- 130

fluence on the direction of the line $s-r$ and only causes a change in the length of the line $s-r$.

From the foregoing it will also be evident that, after the completion of all the adjustments of the notch n^1 , the direction of the line $s-r$ approximately coincides with the wind direction and its length denotes a certain value corresponding to the strength and the altitude of the vessel.

The projection of the sight line now falls in the straight line $s-q$. The point at which the sight line crosses the terrain is denoted by t in Fig. 9. All the dimensions relating to the sighting device are for the sake of clearness in Fig. 9, represented in a considerably larger scale than the dimensions relating to the terrain; the ratio between the lines $s-q$ and $q-t$ is therefore in reality much smaller than shown in the drawing. The point t moves in a straight line $t-u$ which is parallel to the traveling line denoted by the points o, b, r, q, z and which line passes to the left of the target z with the supposed wind direction in Fig. 9.

After the completion of all above named adjustments of the notch n^1 , the vessel will now be steered so far to the side, that the point t follows in the original traveling line $o-b-r-q-z$ when care has to be taken that the vessel again moves parallel to the original traveling line when the point t has attained the above named position. This will be known from the fact that the direction in which the point t is now moving runs through the target z . The position which the sighting device after the above mentioned side movement of the vessel has at a certain moment, is in Fig. 9 denoted by I and shown with dotted lines. The new position of the points q, r, s and t are correspondingly represented with q^1, r^1, s^1 and t^1 . The traveling line coincides now with the straight line r^1-q^1 which is parallel with the original traveling line $o-b-r-q-z$. The point t^1 during further advancement in the course along the line $o-b-r-q-z$ now approaches the target z . As soon as the point t^1 coincides with the target z , that means as soon as the sight line runs through the target, the projectile will be ejected. The position which the sighting device has at this moment, is denoted by II and again shown by dotted lines in the figure. The position of the points q, r and s corresponding to this position are correspondingly represented with q^2, r^2 and s^2 . The point which the projectile hits if it were immune from the action of the wind, will now be represented by x . This point is situated in the traveling line $r^1-q^1-r^2-q^2$ and coincides with the point wherein the "main direction" of the sightline intersects with the terrain, the main direction being projected in the straight line r^2-q^2 . The line $x-z$

must now be parallel to the line r^2-a^2 and consequently also approximately parallel with the wind direction. The length of the line $x-z$ depends substantially only on the length of the line r^2-s^2 or $r-s$ and the altitude of the vessel. As now the length of the line $r-s$ is dependent on the strength of the wind and also on the altitude, it can be so arranged, through suitable selection of the division p^2 corresponding to the strength of the wind and the direction k^1 corresponding to the altitude, that the line $x-z$ obtains a certain predetermined value for each strength of the wind and each altitude. The influence that the wind has on the ejected projectile now causes it not to strike the point x but a point which lies in the direction of the wind, that means approximately in the direction $x-z$ in a definite distance from the point x . The length of this line depends principally on the strength of the wind and the altitude. If therefore the divisions p^2 and k^1 are so selected that the line $x-z$ for a certain strength of wind and of certain altitude is equal to the length of the line which the actual striking point is advanced from the point x with the same strength of wind and altitude, this striking point will fall almost exactly on the target.

As has already been described the turning of the arm M around the axis of the trunnion m^1 corresponding to the altitude is always comparatively small. It will therefore be sufficient in most cases if the arm M has a fixed position corresponding to a certain main altitude, so that it may also be rigidly connected with the slide K .

I claim:

1. A sighting device for air vehicles having a sight bar and a guide therefor, a bracket on which said guide is mounted to oscillate in the side direction around an upright axis, means for setting said sight bar relative to the ejecting angle of the projectile and other means for displacing the sight line in transverse direction relative to the sight bar.

2. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, a reading device adjustable relative to different values of the traveling speed, whereby, on adjusting said device for a given traveling speed said device will indicate the values of the wind strength and wind direction corresponding to each value of the turning angle of said guide in the side direction around said upright axis; the turning angle of said guide out of its middle position being equal to the angle

formed by the longitudinal axis of the vessel with the direction of travel.

3. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, said sight bar being provided with two sighting points of which one is adjustable relative to the sight bar.

4. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, a reading device adjustable relative to different values of the traveling speed, whereby, on adjusting said device for a given traveling speed said device will indicate the values of the wind strength and wind direction corresponding to each value of the turning angle of said guide in the side direction around said upright axis; the turning angle of said guide out of its middle position being equal to the angle formed by the longitudinal axis of the vessel with the direction of travel; said sight bar being provided with two sighting points, and one of said sighting points being adjustable relative to the sight bar, and means for adjusting said movable point sidewise corresponding to the wind direction and radially corresponding to wind strength.

5. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, said sight bar being provided with two sighting points, one of said points being adjustable relative to the sight bar, and means for adjusting said movable point sidewise corresponding to the wind direction and radially corresponding to the wind strength.

6. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, a reading device adjustable relative to different values of the traveling speed, whereby, on adjusting said device for a given traveling speed said device will indicate the values of the wind strength and wind direction corresponding to each value of the turn-

ing angle of said guide in the side direction around said upright axis; the turning angle of said guide out of its middle position being equal to the angle formed by the longitudinal axis of the vessel with the direction of travel; said sight bar being provided with two sighting points, and one of said sighting points being adjustable relative to the sight bar, and means for adjusting said movable point sidewise corresponding to the wind direction and radially corresponding to wind strength.

7. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, said sight bar being provided with two sighting points, one of said points being adjustable relative to the sight bar, a carrier for said movable sight point, and a direction plate on said sight bar, said carrier being adjustable sidewise on said direction plate corresponding to the wind direction.

8. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, said sight bar being provided with two sighting points, one of said points being adjustable relative to the sight bar, a revolute spindle carrying said movable sight point and a support for said spindle, a direction plate on said sight bar constructed to guide said support, said support being displaceable sidewise on said direction plate corresponding to the wind direction, and said spindle being radially adjustable corresponding to the wind strength.

9. A sighting device for air vehicles having a sight bar, and a guide therefor, a bracket with an upright trunnion on which said guide is mounted to oscillate in the side direction, means for setting said sight bar relative to the ejecting angle of the projectile and other means for displacing the sight line in transverse direction relative to the sight bar, a reading device adjustable relative to different values of the traveling speed, whereby, on adjusting said device for a given traveling speed said device will indicate the values of the wind strength and wind direction corresponding to each value of the turning angle of said guide in the side direction around said upright axis; the turning angle of said guide out of its middle position being equal to
